UNITED STATES PATENT OFFICE

105,295

DESIGN FOR A GAME BOARD

George J. Motter, Washington, D. C.

Application May 20, 1937, Serial No. 69,439

Term of patent 3½ years

To all whom it may concern:

Be it known that I, George J. Motter, a citizen of the United States of America, residing at Washington, in the District of Columbia, have invented a new, original, and ornamental Design for a Game Board, of which the following is a specification, reference being had to the accompanying drawing, forming part thereof.

The figure is a plan view of a game board, showing my new design, which has no appreciable thickness. The shading on the drawing indicates contrasting colors.

I claim:

The ornamental design for a game board, as shown and described.

GEORGE J. MOTTER.
